UNITED STATES PATENT OFFICE.

THOMAS HENRY RUSHTON, OF BOLTON, ENGLAND.

STOP-MOTION FOR WINDING-MACHINES.

SPECIFICATION forming part of Letters Patent No. 728,983, dated May 26, 1903.

Application filed June 27, 1902. Serial No. 113,485. (No model.)

To all whom it may concern:

Be it known that I, THOMAS HENRY RUSHTON, machine-maker, a subject of the King of Great Britain, residing at Kay Street Works, 5 Bolton, in the county of Lancaster, England, have invented certain new and useful Improvements in Machines for Winding Yarns and Threads of Cotton, Flax, and other Fibrous Materials, of which the following is a 10 specification.

My invention relates to improvements in machines for winding yarns and threads of cotton, flax, and other fibrous materials; and the objects of my improvements are to simplify and cheapen the construction and to 15 economize floor-space.

In the accompanying two sheets of drawings, Figure 1 is a sectional elevation, and Fig. 2 is a plan, of part of a winding-machine 20 to which my improvements are applied. Fig. 3 is an enlarged detail side view of parts in Fig. 1. Fig. 4 is a plan of Fig. 3 with a few additional parts not included in Fig. 3. Figs. 5 and 6 represent details.

25 In the views, 1 denotes the stand or frame of the machine, 2 the cop box or rail, 3 the cops, 4 the cop-skewer brackets or supports, 5 the rod upon which the cop-skewer brackets are fixed, 6 the stationary thread-guides, 30 7 the drag-board, 8 the pivoted needle-box, 9 detector-needles, 10 rotating wiper-shaft, and 11 a guide roller, pulley, or rod, all the foregoing parts being of the ordinary construction and operating in the usual way, as well 35 understood.

According to my improvements I dispense with the usual longitudinal rails, and I employ one central rail 12, on which are mounted forked brackets 13, supporting the driving- 40 drums 14, which are driven in the usual way by suitable gearing. (Not shown.) This construction and arrangement of one central supporting-rail 12 enables the driving-drums 14 to be brought much closer together than in 45 an ordinary frame, and so economizes floor-space. I also dispense with the usual intermediate rollers or wood blocks and instead drive the flangeless bobbins 15 direct from the drums 14. Consequently the traverse- 50 rods 16 on the opposite sides of the frame for the thread-guides 17 are brought much nearer

together than usual, whereby further floor-space is saved.

The bobbins 15 are supported in improved carriers, each of which consists of a pair of 55 arms 18, mounted upon a stud 19, supported in a bracket 20, carried by the central rail 12, and the bobbins 15 are held normally up to their driving-drums 14 by means of weights 33, suspended from extensions of the arms 18, 60 secured adjustably on the studs 19. (See Fig. 3.) The arms 18 are secured adjustably by means of screws 21 upon the studs 19, each of which is long enough to enable the arms 18 when fixed at its extremities to take the 65 longest bobbin, and by loosening the screws 21 and bringing the arms 18 nearer together and then fixing them in position they can be adjusted to take the shortest or any intermediate length of bobbin. 70

Each traverse thread-guide 17 is pivoted loosely upon its traverse-rod 16, but is connected thereto, so as to move with the rod in its traverse, which may be effected in the usual way by a cam or equivalent. (Not 75 shown.) In the drawings each thread-guide 17 is shown thus held in position by means of a collar 29, placed between the jaws of the divided boss of the thread-guide and fixed on the traverse-rod 16 by a screw 22. A light 80 spring 23 is lapped around the rod 16 and has one extremity secured to the screw 22 and its other end bent over to rest on the thread-guide, and so cause it to bear with a slight but constant pressure upon the yarn 85 wound upon the bobbin 15.

To stop any bobbin 15 on the breakage of one or more of its threads, I employ the pivoted needle-box 8, and in conjunction with this stop-motion or its equivalent I employ a sliding blade 24, of thin sheet-steel or any other suitable metal or material. This blade 24 is fixed upon a vertical rod 25, fitted to slide in a stationary guide 26 and connected at its lower end by a stud 27 to the slotted end of 95 the lever 28, fulcrumed on the bobbin-carrier stud 19. The front end of this lever 28 is bent laterally and then forwardly where it rests normally upon one end of the pivoted needle-box 8; but when a thread (or threads) 100 breaks or fails its corresponding detector-needle 9 falls and coming in contact with the

toothed part 10' on the rotating wiper-shaft 10 is struck, and thereby the pivoted needle-box 8 is moved on its pivots in the direction of the arrow and allows the curved or slotted end of the lever 28 to fall by its own weight assisted by a spring 30. The effect of this movement of the lever 28 is to raise the sliding blade 24, which thereby passes up between, and so separates the bobbin 15 from its driving-drum 14, and so stops the rotation of the bobbin. Simultaneously a rod 31, Figs. 5 and 6, connected to the vertical sliding rod 25, is also raised, and its upper horizontal portion coming in contact with the pivoted traverse thread-guide 17 turns it upward and back 15 clear of the bobbin 15 until it bears against the stationary guide-rod 32, over which the threads pass from the roller or equivalent 11 to the traverse-guide 17 and bobbin 15. 20 When the lever 28 is raised by hand into the position shown best in Fig. 3, the sliding blade 24 is withdrawn, and the bobbin 15, being again in contact with its driving-drum 14, is restarted, and the rod 31 being also drawn 25 down the traverse thread-guide 17 is automatically replaced by gravity and spring 23.

Having now particularly described and ascertained the nature of my said invention and in what manner the same is to be operated, I 30 declare that what I claim, and desire to secure by Letters Patent of the United States, is—

1. In combination in a winding-frame, a single central rail, a series of forked brackets

carried thereby, driving-drums supported by 35 the brackets, a series of flangless bobbins corresponding in number with the driving-drums and in direct contact therewith, a series of loosely-pivoted traverse thread-guides normally maintained in constant contact 40 with the yarn on the bobbins, a pivoted needle-box forming part of a stop-motion for each bobbin, a lever actuated on the breakage or failure of a thread, a sliding blade connected to the lever to separate each bobbin 45 from its driving-drum and a connection therefrom to move the traverse thread-guide out of the way, all substantially as herein described and as illustrated by the drawings.

2. The combination with a pivoted needle-box forming part of a stop-motion, a sliding blade connected with and controlled by the said needle-box, of a loosely-pivoted traverse thread-guide arranged to bear normally on the yarn or its bobbin and on the breakage 55 of a thread to be raised out of the way, means for raising the said thread-guide, a driving-drum for the bobbin and the sliding blade actuated from the said stop-motion to separate the bobbin from its driving-drum, all 60 substantially as herein described and as illustrated by the drawings.

In witness whereof I have hereunto set my hand in presence of two witnesses.

THOMAS HENRY RUSHTON.
